UNITED STATES PATENT OFFICE.

RALPH B. PLATT, OF ST. NICHOLAS, PENNSYLVANIA.

BLASTING-NEEDLE.

SPECIFICATION forming part of Letters Patent No. 288,110, dated November 6, 1883.

Application filed September 7, 1883. (No model.)

To all whom it may concern:

Be it known that I, RALPH B. PLATT, of St. Nicholas, in the county of Schuylkill and State of Pennsylvania, have invented a new and 5 useful Improvement in Blasting-Needles; and I do hereby declare that the following is a full, clear, and exact description of the same.

This invention relates to the art of blasting coal, rock, and similar material; and it consists of a needle made with a copper tip or point to prevent striking fire, and with one or more holes through the opposite end for cutting off the end of the "squib" or straws used in priming the charge.

15 The accompanying drawing illustrates my invention by a side elevation.

Similar letters of reference indicate corresponding parts.

A is the needle, made of any desired size 20 and length, with its pointed end made of copper, as seen at B. At the upper or butt end are one or more holes, C C, bored square through, as shown.

D is the ring or handle-eye, by means of 25 which the needle is withdrawn. In blasting, a squib made of paper or similar material is filled with powder, (a straw is sometimes used,) one end of which is closed with soap or similar material, forming a sort of bottom to prevent

30 the powder from escaping. This end must be cut off before the squib or straw is inserted into the hole made by the needle. This cutting off is usually done with the teeth of the operator; but when straws are used the teeth split the

35 straw, and frequently ruin it, causing much delay and consequent loss. To avoid this difficulty, the end of the straw is thrust through

one of the holes C, when by a slight downward pressure the straw is cut off square and clean. These holes C C are of different sizes, 40 to fit straws of different diameters.

In blasting rock or coal the practice is to insert the needle in the cartridge, and then tamp earth or other suitable material around it in the drill-hole. When the tamping is finished, the needle is drawn out and the squib inserted in its place. If that fails to ignite, the needle has to be inserted anew, and in so doing there is liability of producing a premature explosion by the iron or steel point striking fire by contact with sulphur or spar contained in the rock or coal, either above or below the cartridge. With a needle provided with a copper point such a result cannot be produced.

55 The body of the needle is made of iron or steel, in order that it may have the requisite strength, rigidity, durability, and cheapness.

Having thus described my invention, I claim as new and desire to secure by Letters Patent— 60

1. As an improved article of manufacture, a blasting-needle having its upper end made of steel or iron, and provided with a handle-eye, D, and cutting-holes C C, located in the shank, and having a copper point, B, as set 65 forth.

2. A blasting-needle having one or more cutting-holes, C C, of different diameters, located in the shank, substantially as shown and described.

RALPH B. PLATT.
